United States Patent Office

Des. 182,728
Patented May 6, 1958

182,728

BOAT

Wilmer L. Kinzie, Alva, Okla.

Application February 25, 1957, Serial No. 44,976

Term of patent 3½ years

(Cl. D71—1)

Fig. 8.

Fig. 9.

Fig. 1 is a top plan view of the boat, showing my new design;

Fig. 2 is a side elevational view thereof;

Figs. 3 to 7 inclusive are phantom outline views thereof taken on lines 3—3 to 7—7 respectively of Fig. 1 to reveal precise contours at those transverse planes;

Fig. 8 is a top perspective view of the boat; and

Fig. 9 is a rear elevational view thereof.

I claim:

The ornamental design for a boat, as shown.
